ROBERT T. HAZELTON, OF CINCINNATI, OHIO, ASSIGNOR TO THE CINCINNATI MILLING MACHINE COMPANY, OF OAKLEY, OHIO, A CORPORATION OF OHIO.

VERTICAL MILLER.

1,295,746.

Specification of Letters Patent.

Patented Feb. 25, 1919.

Application filed May 5, 1917. Serial No. 166,668.

To all whom it may concern:

Be it known that I, ROBERT T. HAZELTON, a citizen of the United States, and residing at Cincinnati, in the county of Hamilton and State of Ohio, have invented a new and Improved Vertical Miller, of which the following specification is a full disclosure.

This invention deals with machine tools and, in its preferred embodiment, it relates more particularly to milling machines of the type employing a spindle mounted in a shiftable head, such as frequently obtains in so-called "vertical" millers.

A prerequisite of a commercially satisfactory milling machine is a smooth-running non-vibrating spindle.

This desideratum has been obtained in the case of certain types of milling machines in which the spindle is mounted in fixed non-shiftable bearings having an invariable relation with the driving elements. In designing a certain species of vertical miller, difficulty has been experienced in securing an absolutely smooth-running spindle. It has finally been ascertained that this is attributable to certain torsional strains or stresses occasioned in the spindle as a result of certain "settings" of the head; the head in this being designed to be shiftable bodily.

A primary object of this invention is, accordingly, to create a milling machine having a shiftable spindle-carrying head so designed and constructed as to insure identical propelling conditions in all "settings" of the head to reduce to the minimum torsional strains occasioned by the driving gears.

Other objects will be in part obvious from the annexed drawings and in part indicated in connection therewith by the following analysis of this invention.

This invention accordingly consists in the features of construction, combination of parts and in the unique relation of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and

ence denote corresponding parts throughout all the views, of which—

Figure 1 is a vertical elevation, mainly in section showing the interior of a vertical miller embodying this invention. Fig. 2 is a front elevation of the spindle-carrying head. Fig. 3 is a top view or plan thereof. Fig. 4 is a detail of a hand-wheel for shifting the gears. Fig. 5 is a fragmentary detail showing the shifting fork.

Continuing with reference to the drawings, A indicates a column or main frame of the machine which suitably supports the table Z; preferably through the agency of the interposed saddle Y and knee X. In this case the knee X is vertically shiftable along the ways 4 and the saddle Y is laterally shiftable on the knee X along the ways 5 and the table Z is transversely shiftable on the saddle Y along the ways 6; all in a conventional manner.

The spindle W is arranged vertically in the head and in accordance with the design herein illustrated, it is so mounted as to permit of it being shifted in the direction of its axis, which in this case is up and down. To that end the head proper B of the column A terminates in a supplemental or auxiliary head C which is shiftable thereon in the direction of the axis of the spindle. As shown by Fig. 3 the main head B and the supplemental head C have complementary interfitting slideways 7, and the main head B carries rails 8 and 9 bolted thereto for the purpose of keeping the main and auxiliary heads together. The spindle W is journaled permanently in the auxiliary sliding head C by being provided with a tapered bearing at its lower end and a thrust bearing at its upper end. Thus, at its lower end the supplemental head C carries a bushing or bearing 10 which is tapered to flare downwardly and is adapted to fit with a correspondingly tapered portion 11 of the spindle. This bearing runs snugly and, being very close to the lower extremity or tool-carrying portion of the spindle W, insures smooth cutting free from chatter.

At its upper end, the spindle W has a portion 12 of uniform diameter which is journaled in a bushing 13 secured to the upper end of the supplemental head C. This bushing is stepped, as illustrated, so as to serve as a thrust element. The uppermost end of the spindle W is threaded, as indicated 110

by 14 and carries a suitable collar 15 which, through the interposed ring 16 is enabled to take the thrust and prevent the spindle from lowering.

5 The spindle is practically driven by means of one or more gears secured thereto in rigid relation therewith, and in such a manner as to eliminate or reduce to a minimum any torsional strains from the gears to the driving or tool-carrying end of the spindle. The construction preferably embodies a massive sleeve D which, at its lower end, has a tapered bore adapted to receive a prolongation of the tapered portion 11 of the 10 spindle, and also to carry a key 17 located quite near to the tapered journal of the spindle, and thereby locate the ultimate driving point thereof close to the working end of the spindle and consequently shorten such 15 portions of the spindle as are obliged to carry a torque. The upper end of the sleeve D snugly fits the spindle portion 18 of uniform diameter, and said sleeve is maintained snugly against the tapered portions 11 by 20 means of a nut 19. The sleeve D has one or more driving gears affixed thereto. Thus, a small diameter gear or pinion 20 is secured to its upper end and a large diameter gear 21 is secured between the pinion and the 25 lower end of the sleeve D.

It will be perceived that, in consequence of the foregoing construction, the transmission of the propelling force from either of the gears 20 or 21 to the tool-carrying extremity of the spindle is always the same, irrespective of the positions occupied by the supplemental head C on the main head B. The gear sleeve D being at all times fastened solidly to the spindle, the only region of said 30 spindle subjectable to torsional strains is that between the key 17 and the lower extremity of the spindle W.

When the bolts 22 are loosened, and the supplemental head C is shifted on the main head B, no alteration in the relations of the gears 20 and 21 to the spindle can result.

The main source of power is the driving pulley E suitably located at one side of the column A. A shaft 1 is journaled in the bearing portions 23 and 24 and to this shaft are splined the shiftable members F and G carrying respectively the gears a, a', e and m. A parallel shaft 2 is journaled adjacent the shaft 1 and has fixed thereto corresponding 50 gears a', c', c' and m' adapted to be brought into mesh with the respective first mentioned gears by conventional shifting levers not here shown. Another parallel shaft 3 is journaled adjacent to shaft 2 and carries a 55 sliding member H provided with gears a'' and n adapted to be brought into mesh with the corresponding gears a' and n' respectively fixedly mounted on the shaft 2. The shaft 3 has a bevel gear 25 fixed to its extremity and this bevel gear meshes with an-

other bevel gear 27 keyed to the lower end of a vertical shaft J arranged parallel with the axis of the spindle W and adjacent thereto. A cup K is fixed within a bore in the frame B in the manner shown by the drawings and 70 it is provided with a trough-like portion 28 adapted to receive oil and assist in the lubrication of the bevel 27. A bushing 29 may be arranged between the journal on the shaft J and the cup K, as shown, thereby providing for effective lubrication and the like. The upper end of the shaft K is likewise journaled, through the intermediary of a bushing 30, in the head B, and it is provided with a retaining ring 31 and an oil-guard 80 32, constructed and arranged as shown in the drawings. The intermediate portion 33 of the shaft J is of uniform diameter from end to end and is provided with an elongated feather or spline 34 which interfits 85 with a gear member M adapted freely to slide on the portion 33 of the shaft J and to be affixed in any appropriate position thereon. This member M is provided with two gears o and r which, in appropriate positions, of the gear member M may be meshed with the gears 20 or 21, respectively of the sleeve D.

Referring to Fig. 4, there will be seen a hand-wheel P mounted in the shiftable auxiliary head C so as to move bodily therewith. The shaft 35 is journaled in the part 36 and its axial shift is limited in the one direction by the shoulder 37 and is permitted in the outward direction by a spring 38 compressed between the part 36 and the pinion 39 at the end of shaft 35. The extremity of said shaft assumes the form of an indexing pin 40 which may enter either hole 41 or hole 42 (see Fig. 5) and thereby position a gear-shifting fork R appropriately for meshing gear r with gear 21, or gear o with gear 20, as the case may be.

The yoke or fork R has a sliding fit with the shaft S, which is secured to the head C and it has a bifurcated extension 43 adapted to engage the gear member M to shift it up or down. A rack 44 is fixed to the yoke R and is engaged by the pinion 39.

When it is desired to shift the gear-member M so as to connect into operation either gear o or r, it is only necessary to pull out the pilot wheel P to disengage pin 40 from the hole 41 or 42, and then rotate the wheel until the pin 40 snaps back into the other hole; when the parts will be interlocked with the gears properly intermeshing.

Having thus revealed this invention, I claim as new the following combinations of steps and elements or equivalents thereof, and desire to secure the same by Letters Patent of the United States:—

1. A vertical milling-machine combining a column having an overhanging head; an auxiliary head vertically adjustable at the 130

- extremity of the main head; a spindle journaled vertically in the auxiliary head; a driven gear keyed fast to said spindle; a gear shiftably mounted in the main head to mesh with said first mentioned gear in any predetermined position of the auxiliary head; hand operated means for shifting said gear and adapted to retain it in mesh, and a transmission for driving said last mentioned gear. 5 60
2. A vertical milling-machine combining a column providing an overhanging main head; an auxiliary head shiftably mounted on said main head; a spindle journaled in said auxiliary head; a gear fixed to said spindle; a shaft journaled in said main head parallel with said spindle; a driven gear shiftably co-axially with said shaft into mesh with the driven gear in all positions of the auxiliary head; manually-operated means for effecting said shifting and adapted to retain said gears in mesh, and a power transmission for propelling said driven gear. 10 70
3. A machine tool combining a frame forming a main head; an auxiliary head shiftably thereon; a shaft journaled in the main head; a gear splined to said shaft; a yoke for shifting said gear and having a rack; and a pinion journaled in said shiftable auxiliary head and means whereby said pinion is held intermeshing with said rack in all positions of said auxiliary head. 15 75
4. A machine tool combining a frame forming a main head; an auxiliary head shiftably thereon; a shaft journaled in the main head; a gear splined to said shaft; a yoke for shifting said gear and having a rack; a pinion journaled in said shiftable auxiliary head and intermeshing with said rack in all positions of said auxiliary head; and means for interlocking the pinion and yoke. 20 80
5. A machine tool combining a frame forming a main head; an auxiliary head shiftably thereon; a shaft journaled in the main head; a gear splined to said shaft; a yoke for shifting said gear and having a rack; a pinion journaled in said shiftable auxiliary head and intermeshing with said rack in all positions of said auxiliary head; and means for interlocking said pinion in a plurality of independent relations with said yoke. 25 85
6. A machine tool combining a frame forming a main head; an auxiliary head shiftably thereon; a shaft journaled in the main head; a gear splined to said shaft; a yoke for shifting said gear and having a rack; a pinion journaled in said shiftable auxiliary head and intermeshing with said rack in all positions of said auxiliary head; and means for interlocking said pinion in a plurality of independent relations with said yoke. 30 90
- main head; a gear splined to said shaft; a yoke for shifting said gear and having a rack; a pinion journaled in said shiftable auxiliary head and intermeshing with said rack in all positions of said auxiliary head; a hand-wheel for manually rotating said pinion to shift said yoke; and means for maintaining the pinion and yoke in more than one predetermined relation. 35 95
7. A vertical milling-machine combining a column having an overhanging head; an auxiliary head vertically adjustable at the extremity of the main head; a spindle journaled vertically in the auxiliary head; a plurality of differently diametered gears keyed fast to said spindle; a plurality of complementary gears shiftably mounted in the main head, means whereby either of said complementary gears may be retained directly in mesh with the corresponding one of said first-mentioned gears in any predetermined position of the auxiliary head; means for retaining said gears in mesh and a transmission for driving said last mentioned gear. 40 100
8. A vertical milling-machine combining a column providing an overhanging main head; an auxiliary head shiftably mounted on said main head; a spindle journaled in said auxiliary head; a number of differently diametered gears fixed to said spindle; a shaft journaled in said main head parallel with said spindle; a corresponding number of complementary driven gears shiftably co-axially with said shaft directly into mesh with one or any of the driven gears in all positions of the auxiliary head; and a transmission for propelling said driven gears. 45 105
9. A vertical milling-machine combining a column providing an overhanging main head; an auxiliary head shiftably mounted on said main head; a spindle journaled in said auxiliary head; a gear set fixed to said spindle; a shaft journaled in said main head parallel with said spindle; a complementary gear set splined to said shaft; a transmission for driving said shaft; and means mounted on said shiftable head for manually shifting said last mentioned gear set. 50 110

In witness whereof, I hereunto subscribe my name, as attested by the two subscribing witnesses.
